VEHICLE FRAME AND BACKHOE

Gerard S. Gremillion, 50 E. 54th St., Kansas City, Mo. 66106, and Bert M. McMillin, 10120 Wenonga Lane, Leawood, Kans. 66206

Filed Mar. 19, 1971, Ser. No. 126,400

Term of patent 14 years

Int. Cl. D12—J3
U.S. Cl. D14—3 R

Fig. 3.

Fig. 5.

FIG. 1 is a top plan view of a vehicle frame and backhoe embodying the unique design;

FIG. 2 is a side elevational view of the vehicle frame and backhoe shown in FIG. 1;

FIG. 3 is a side elevational view of the opposite side of the vehicle frame and backhoe from that shown in FIG. 2;

FIG. 4 is a rear elevational view of the vehicle frame and backhoe shown in FIG. 3; and

FIG. 5 is a front elevational view of the vehicle frame and backhoe shown in FIG. 4. The vehicle shown in broken lines in FIG. 2 is included for illustrative purposes only.

We claim:

The ornamental design for a vehicle frame and backhoe, as shown and described.
